DEMOLITION BOMB

Worth C. Goss, Seattle, Wash.

Application October 19, 1942, Serial No. 462,490

2 Claims. (Cl. 102—2)

1

This invention relates to improvements in demolition bombs, and in the methods of their manufacture, and the means for and methods of effecting the simultaneous detonation thereof. This application is being filed as a continuation in part of copending application Serial No. 362,443.

More particularly, this invention has to do with demolition bombs of exceedingly large size; that is, bombs weighing upwardly of five tons, and of a kind especially applicable for the bombing of battleships, fortifications, manufacturing plants and other military objectives by dropping the bombs from aircraft.

It will here be stated as explanatory to the present invention that the bombing of warships, fortifications, and military objectives, as is carried on in present-day warfare by the dropping of bombs from airplanes, is quite common. However, the extent of use of these bombs of larger sizes is limited by, or at least is dependent to a material extent, upon the distances to which they have to be transported, the speed of the airplane carrying them, its cruising range and the load the plane is capable of transporting. In view of this, it is manifest that it is extremely desirable to increase the effectiveness or destructiveness of bombs as much as possible without requiring the increase in their weight. In other words, it is desirable to increase the relative effectiveness of bombs as much as can be beyond that now possible, along with any increase in size, or increase in weight of the bomb. Furthermore, any single bomb that can be made to fully accomplish the destruction of an object at which it is aimed, is worth any number that can only partially accomplish that end.

It will also be here mentioned in connection with the present invention, that to obtain the full effect of any charge of explosive material in a bomb; for example, such material as T. N. T., amatol, or other explosives now used, it is extremely important that detonation throughout the entire body or volume of the charge should be instantaneous and complete. Otherwise, the

explosion of one part of a charge of explosive may act to scatter the remainder of the charge to such extent that its full force and effect will be materially reduced. This difficulty has been experienced in present-day bombs of large size, and in many instances, it has been disclosed that because the detonation of the charge was progressive instead of instantaneous, the bomb failed to accomplish the possible and desired results.

2

In view of the foregoing, it has been the principal object of the present invention to provide means and methods whereby to increase the effectiveness and destructiveness of demolition bombs and especially bombs of the larger sizes, including the provision of means for causing the complete and simultaneous detonation of the bomb throughout its entire volume.

More specifically stated, it has been an object of the present invention to obtain the complete and simultaneous detonation of a charge of explosive as used in a bomb of exceptionally large size by effecting the simultaneous detonation of a plurality of booster charges of material, distributed at uniformly spaced intervals throughout the body of the main charge; each booster charge being adapted to be detonated by the exploding of a cap or fuse therein and all fuses of the bomb being connected in a circuit through which a powerful electric current of high voltage will be closed by the striking of the falling bomb, thereby to cause the instantaneous firing of all fuses and the resultant instantaneous detonating of all booster charges and the complete instantaneous detonation of the bomb.

Still further objects of the present invention are to be found in the structure of the fuses; in the manner of arranging the several fuses in the circuit, and in the means for supplying and for applying the current to the circuit at the desired time and at the required voltage.

It is also an object of the invention to provide a bomb shell or casing constructed of parts of novel form and of novel arrangement whereby cost of manufacturing is lessened and assembly is expedited.

Still other objects of the invention reside in the methods of assembly of parts comprising the shell or case of the bomb, its charge, and its detonating apparatus.

In accomplishing these and other objects of the invention, I have provided the improved details of construction, the preferred forms of which are illustrated in the accompanying drawings, wherein—

Fig. 1 is a side view of a demolition bomb embodying the present invention.

Fig. 2 is a longitudinal sectional view of the bomb taken in its axial line.

Fig. 3 is an upper end view of the bomb showing the guiding fins.

Fig. 4 is a nose end view of the bomb, showing the cutting fins.

Fig. 5 is a cross section taken on the line 5—5 in Fig. 2.

Fig. 6 is an enlarged, cross sectional detail of the nose end of the bomb, illustrating diagrammatically the arrangement therein of the current supply and circuit closing devices for the detonation of the charge.

Fig. 7 is an enlarged sectional detail of one of the booster charges and the detonating fuse applied thereto.

Fig. 8 is a perspective view of one of the detonating fuses.

Fig. 9 is an enlarged, sectional detail illustrating joined portions of the shell, or case of the bomb.

Fig. 10 is an enlarged, cross section through the bomb on line 10—10 in Fig. 2, showing the positioning of the booster charges at any selected horizontal level.

Referring more in detail to the drawings—

First describing the construction of the present bomb, as seen in Fig. 1, in a general way, and bearing in mind that it concerns bombs of the larger sizes; that is, bombs which may have a diameter of three feet or greater and an overall length of from fifteen to twenty feet and weighing in the neighborhood of five tons: The main body portion 1 of the shell or bomb case is of tubular and cylindrical form, uniform in diameter throughout its length, which is equal approximately to half the overall length of the bomb. At the lower end of the bomb is a pointed nose section 2, and at the upper end is the tail section 3.

The nose portion 2 is a heavy steel forging or casting, tapered to a rather elongated point. It is open at its upper end and is there equal in diameter to the diameter of the main body and is permanently joined thereto in a welded seam, as indicated at 4 in Figs. 2 and 6.

Welded onto the exterior of the nose portion 2, at equal intervals thereabout and extending lengthwise of the bomb axis, are four shear blades 5, tapered to and joined in a point somewhat beyond the point of the body portion of the nose 2. These blades are designed to pierce and then cut through an object to facilitate its destruction by the bomb.

Interiorly the nose section is hollow, and its side walls are gradually thickened toward the point. The lower portion is internally braced and strengthened by the formation of radial ribs or webs 6, as shown in Figs. 2 and 5.

The upper or tail section 3 of the bomb case comprises a semi-spherical cap or closure portion 8 and the guiding fins 9—9 that are mounted thereon. These fins are crossed at right angles, as noted in Fig. 3, and are of substantial length, flared toward their upper ends, and welded at their lower ends to the cap. The arrangement of fins is symmetrical with reference to the axial line of the bomb, and they serve to guide and maintain the equilibrium of the bomb as it falls, causing it to strike nose first.

To facilitate the assembly of the tail section with the bomb body, the body is equipped with an internally extending collar 12, as observed best in Fig. 9, that is threaded into the downwardly opening end of the cap. As shown in Fig. 9, the band or collar 12 is fitted within the upper end of the body cylinder and is secured by a welded seam 13. Part of the band extends beyond the upper end of the cylindrical body and is externally threaded. This is threaded into an internally threaded band 14 that is welded, as at 15, onto the periphery of the cap as an extension thereof. The threading of the parts 12 and 14

is accomplished prior to their application to the body cylinder and cap, and the welding is done before the shell receives the charge of explosive. When the parts are assembled, the cap and body engage solidly together in a flush joint.

The present invention contemplates filling the entire shell with a very powerful explosive, except for a small space in the nose section, left for containing the current supply means and firing mechanism. The explosive material is designated herein by reference numeral 18 and by reason of its character and the possibility of that which is contained in the lower portion of the case being crushed by the weight of that supported above it, it is preferred that supporting shelves 19 as required be located in the shell at suitable intervals. These shelves rest at their peripheral edges on flanges 20 fixed to the interior of the shell body, and in the shelves, openings 21 as required would be provided for the passage of circuit wires as will later be described. The explosive 18 is most generally in the form of pressed bricks and these are stacked in place and the open intervals filled later with material tamped in.

In view of the large quantity of explosive used and the length and diameter of the shell case, it is essential in obtaining simultaneous detonation, to distribute booster charges of suitable explosive such as T. N. T. throughout the main charge and to arrange for the simultaneous detonation of these booster charges which effect the simultaneous detonation of the main charge. In Figs. 2 and 10, I have illustrated the present preferred disposition of the booster charges, which are of block form and designated by reference numeral 22.

In the assembling of the bomb, the mechanism for supplying current and setting off the bomb, is first placed in position in the nose section 2 and covered by a plate 25 as indicated in Fig. 2. Then the explosive 18 is filled in and at the proper and selected places, the booster charges 22 are placed in position somewhat within the shell. Immediately above each horizontal group of booster charges, I place a shelf 19, then more explosive is placed in position, building up in this manner until the shell is filled. Finally the tail section 3 is threaded into place.

To provide for the simultaneous detonation of all the booster charges, I employ the mechanism which has been shown to best advantage in Figs. 6, 7 and 8. Each booster charge 22 is there shown as being equipped internally with a firing cap 30. All caps are electrically fired, by means presently described in detail, upon the closing of an electric circuit therethrough, and the closing of this circuit is under control of a firing rod 35 that is contained slidably in an axial bore 36 opening through the point of the nose as seen best in Fig. 6.

At its outer end, the rod 35 has a head or cap 38, normally located somewhat beyond the nose point. At its inner end the rod has a piston portion 39 reciprocally fitted in an air cylinder 40. The cylinder has a channel 40' (see Fig. 6) leading therefrom into a diaphragm chamber 41 covered by a flexible diaphragm 42. When the rod 35 is driven inwardly by impact of its head portion against an object, air is driven from the cylinder into the chamber 41, the diaphragm 42 is moved outwardly, thereby to act against an arm 43 of a bell crank lever 44, to rock the lever and cause the other arm 43' thereof to close an electric circuit. Normally the rod 35 is held extended

by any suitable yieldable means, such as a coiled spring 45 located in the air cylinder as noted in Fig. 6.

Referring now to Figs. 2 and 6, it will be understood that each of the booster charges 22 has a detonating fuse or cap 30 set therein. Extending from each cap are circuit connections 51 and 52. All caps of all booster charges in the bomb are connected in series circuit with a condenser 60; the connection being as diagrammatically shown in Fig. 2, through circuit wires 61 and 62 leading respectively to one terminal 63 of the condenser and to the bell crank 44, which is of an electrically conductive material. When the bell crank is rocked by the expansion 15 of the diaphragm 42, it causes the arm 43' to engage the other terminal 64 of the condenser, thereby to close the circuit through all fuses.

To charge the condenser, I have located a battery 70 in the nose of the shell case. This has one circuit connection 71 with the condenser terminal 64, and another connection 72 leading to a switch 75 from which a wire 76 leads to the terminal 63 of the condenser. Upon closing the switch 75, the battery starts to dissipate its charge to the condenser, and it is anticipated that this switch shall be closed about five to ten minutes before the bomb is to be dropped.

The switch may be of any kind suitable to be mounted in the shell case, where it can be manually closed, such as by turning in a plug or screw.

To facilitate the assembly of the booster charges and the circuit wiring therefor, it is desirable that the shell body be provided at locations opposite each booster charge with a threaded opening 80 fitted with a plug 81. Prior to applying the explosive charge and plugs, circuit wires, as at 82 which connect the fuses in series circuit, are located inside the shell case with ends extended out through the openings 80. After the charge has been placed, and the shell case closed, then the ends of the circuit wires extended from any opening are attached to the terminal connections 51 and 52 of the corresponding fuse, and the fuse is then inserted through the opening 80 and seated in the hole provided for it in the block of booster charges. Then the plugs 81 are applied to the openings in the case.

As shown in Fig. 7, the fuses finally are inserted in holes provided therefor in the blocks 22 which comprise the booster charges. The preferred type of detonating fuse is illustrated in Figs. 7 and 8 wherein 85 designates a cylindrical copper casing having a filler 86 comprising a quantity of tetryl, held by a plug of fulminate 87. A special heater wire 88 extends between the inner ends of the fuse circuit terminals 51 and 52, and wrapped about this and embedded in the fulminate 87 is a micro-sheet of explosive 90. The circuit wires 51 and 52 are held in place by a plug of sulphur filler, 91, overlying a Bakelite plug 92 fitted in the casing 85.

With this arrangement of parts, it is quite apparent that, assuming the switch 75 to have been closed for a period of time sufficient for 65

the condenser to absorb the charge from the battery 70, it is understood that instantly upon closing of the circuit by the action of the bell crank 44 as moved by the rod 35, the full force of the powerful voltage of the condenser charge will be applied to the circuit, passing through all the fuses 88 and literally blows them to pieces with the instantaneous detonation of all booster charges and thus causing complete and simultaneous detonation of the entire charge.

The particular advantage to be gained by this arrangement of booster charges and their detonating fuses resides in the fact that at a plurality of locations, the main charge can be simultaneously detonated, thereby decreasing the extent to which the detonating wave must travel to the distance between booster charges, and this distance can be made only a very small fractional part of the distance from end to end of the bomb.

I claim:

1. A demolition bomb comprising a hollow metallic casing capable of withstanding considerable internal pressure, a detonatable material substantially filling the casing, a plurality of detonating units embedded in said material at uniform intervals of spacing throughout the length of the casing; each of said units including a block of highly explosive material, a detonating cap in the block, and a heater wire for the cap adapted to be exploded by electrical impulse, a storage battery in the casing, a condenser having an electrical connection with said battery to receive its charge, a normally open switch in the connection, an electric circuit joining the heater wires of all units in a normally open series circuit, and a switch in the circuit adapted to be closed by impact of the bomb with an object.

2. A demolition bomb as recited in claim 1 wherein said normally open switch in the connection between the storage battery and the condenser is disposed in the casing and adapted to be closed from the outside thereof to permit the dissipation of the battery charge to the condenser.

WORTH C. GOSS.
